ADJUSTABLE EYEBOARD

Robert R. Barnes, Candler, James F. Keith, West Asheville, and Charles C. Robinson, Jr., Enka, N. C., assignors to American Enka Corporation, Enka, N. C., a corporation of Delaware

Application May 18, 1953, Serial No. 355,462

5 Claims. (Cl. 28—55)

The present invention relates to an adjustable eyeboard to be used in conjunction with a slashing, warping, or other machine which will allow for or require the regulation of the width of the warp passing therethrough.

Normally when passing filaments, threads, yarn or the like, hereinafter designated as threads, from creels or other supply sources through any of the machines previously mentioned, the threads, in order to form a particular width warp, pass through an eyeboard containing holes positioned in substantially vertical rows with the horizontal distance between the outermost holes defining the width of the warp desired. Each time that a modification is desired either in the width of the warp with the number of threads remaining the same or in the number of threads with the width remaining the same, the operator is required to stop the machine, remove all of the threads being passed through the eyeboard, replace the eyeboard with a different one having the desired number of equally spaced holes for the desired width of warp, thread the new eyeboard and again put the machine into operation. The steps of replacing and threading the eyeboard have resulted in a considerable loss in operating time for the machine. In view of this loss of operating time the eyeboard of the present invention has been developed to substantially minimize the time required by the operator to obtain the above referred to modifications.

Broadly, this invention provides an adjustable eyeboard composed of a plurality of sections which are movable to and from each other contiguously in the same plane. More particularly, this invention provides an adjustable eyeboard comprising a frame having upper and lower channels therein, a plurality of sections having holes therein slidably mounted in the channels, lost motion links connecting the sections and a turn buckle arrangement operatively connected to the sections to move them to and from each other.

It is therefore an object of this invention to provide a novel adjustable eyeboard which will allow for the regulation of the spacing between the threads passing therethrough and thereby the regulation of the width of the warp.

Other objects and advantages of this invention will become apparent from the following detailed description when considered in conjunction with the accompanying drawings, wherein:

Figure 1 is a view in elevation of the eyeboard of this invention; and

Figure 2 is a sectional view taken along line 2—2 of Figure 1.

Referring to the drawings and more particularly to Figure 1, the numeral 10 indicates an eyeboard composed of two end sections 11 and 12 and a plurality of intermediate sections 13. Each of said sections has holes 14 therein through which threads pass when being conveyed from the creels to the slashing machine. The holes 14 are so arranged in the eyeboard that they form a plurality of parallel rows departing slightly from the vertical which

2

allow for more equally spaced threads per unit width of the warp.

End sections 11 and 12 and intermediate sections 13 have top and bottom parallel sides 15 and 16, respectively. Intermediate sections 13 also have parallel sides 17 and 18 which are parallel to the rows of holes passing through the intermediate sections and form an oblique with the top and bottom parallel sides 15 and 16, respectively. End sections 11 and 12 each have a side 19 and 20, respectively, which are parallel to the rows of holes in each section and the oblique sides 17 and 18 of the intermediate sections. Positioned at the top and bottom of sections 11, 12 and 13 are lost motion links 21 which interconnect the sections and define the maximum spacing between the sections.

Enclosing sections 11, 12 and 13 is a frame 22. Frame 22 is composed of end members 23 and top and bottom members 24 and 25, respectively. Bottom member 25 is formed of three laminated plates 26, 27 and 28 and compression plates 29 and 30. Plates 26 and 28 (as shown in Figure 2) are of greater width than plate 27 so that upon being assembled they define a channel in the bottom member 25 within which the lower portions of sections 11, 12, and 13 may slide. The top frame member 24 is formed of laminated plates 32 and 33, flanged plates 34 and 35, and compression plates 36 and 37. As shown in Figure 2, flanged plates 34 and 35 are much wider than laminated plates 32 and 33 so that upon being assembled they form a channel within which the lost motion links 21 and top portions of sections 11, 12 and 13 may slide.

Again referring to Figure 1, the means for moving the sections to and from each other contiguously include sleeve members 38 and 39 attached to the end-sections 11 and 12, respectively. Passing through sleeves 38 and 39 is a shaft 40 having two threaded portions thereon.

Shaft 40 passes through each of the sleeves in a threaded relationship so that one threaded portion passes through the sleeve of section 11 while the other portion passes through the sleeves of section 12. The threaded portions of shaft 40 are oppositely threaded so that depending upon the direction of rotation of the shaft the end-sections 11 and 12 will move either toward or away from each other. Supporting shaft 40 are end members 23 and support 41. Preventing longitudinal movement of shaft 40 in the frame 20 are thrust shoulders 42 and 43 on each end of the shaft formed from a reduction in the diameter of shaft 40. Attached to the portion of shaft 40 extending beyond the frame members 23 by a set screw is crank 44 which upon being rotated results in the expansion or contraction of the eyeboard.

With the parts constructed and arranged substantially as hereinbefore described, the operation, briefly stated, is as follows:

As shown in Figure 1 the eyeboard is in a contracted position but rotation of the crank will first move the end sections away from each other followed consecutively by the outermost intermediate sections until the lost motion is taken up by the links whereupon the eyeboard is in its expanded position. Rotation of the crank in the opposite direction will accordingly move the sections together.

By this invention operators without exchanging eyeboards may now change the width of the warp and the number of threads going to make up said warp in a minimum amount of time and with a minimum amount of effort.

What is claimed is:

1. An eyeboard comprising a rectangular frame having upper and lower elements as the two longer sides, said upper and lower elements defining channels; a plurality of

sections having top and bottom parallel sides slidably mounted within said channels with at least one of the remaining sides of each section forming an oblique with said parallel sides and having at least one row of holes in each section parallel to said oblique sides of said section through which threads may pass, said rows being parallel to each other, a rotatable shaft mounted above and parallel to the channel in said upper element and means responsive to the rotation of said shaft to move said sections to and from each other contiguously.

2. An eyeboard comprising a substantially vertical rectangular frame having upper and lower elements as the two longer sides, said upper and lower elements defining channels; a plurality of sections having top and bottom parallel sides slidably mounted within said channels with at least one of the remaining sides of each section forming an oblique with said parallel sides and having at least one set of holes in each section parallel to said oblique sides of said sections through which threads may pass, said rows being parallel to each other; lost motion linkages interconnecting said sections at the bottom and at the top, a rotatable shaft mounted above and parallel to the channel in said upper element, and means responsive to the rotation of said shaft to move said sections to and from each other contiguously.

3. An eyeboard comprising a substantially vertical rectangular frame having upper and lower elements as the two longer sides, said upper and lower elements defining channels; two sections having top and bottom parallel sides slidably mounted within said channels with at least one of the remaining sides of each section forming an oblique with said parallel sides and having at least one row of holes in each section parallel to said oblique sides of said sections through which threads may pass, the said rows being parallel to each other; at least one sleeve mounted on one of said sections; a shaft passing through the sleeve and threadably connected thereto; and means mounted on said shaft to rotate the same.

4. An eyeboard comprising a substantially vertical rec-

tangular frame having upper and lower elements as the two longer sides, the said upper and lower elements defining channels; a plurality of sections having top and bottom parallel sides slidably mounted within said channels with at least one of the remaining sides of each section forming an oblique with said parallel sides and having at least one row of holes in each section parallel to said oblique side of said section through which threads may pass, the said rows being parallel to each other; at least one sleeve mounted on each of two said sections, a shaft passing through said sleeves and oppositely threadably connected thereto; and means mounted on said shaft to rotate the same.

5. An eyeboard comprising a substantially vertical rectangular frame having upper and lower elements as the two longer sides, the said upper and lower elements defining channels; two end sections and a plurality of intermediate sections, each of said sections having top and bottom parallel sides slidably mounted within said channels, said intermediate sections also having parallel sides oblique to said top and bottom sides, each of said end sections having a side parallel to said oblique sides of said intermediate sections, each of said sections having at least one row of holes therein through which threads may pass, all rows of said sections being parallel to said oblique sides of said sections; at least one sleeve mounted on each of said end sections; a shaft passing through said sleeves and oppositely threadably connected thereto; lost motion linkage interconnecting said sections; and means mounted on said shaft to rotate the same.
